FILTERING AGITATOR

Andrew H. Gerhardt, Birmingham, Mich., and Charles R. Waldrop, Herrin, Ill., assignors to Borg-Warner Corporation, Chicago, Ill., a corporation of Illinois
 Continuation of application Ser. No. 747,373, July 9, 1958. This application Nov. 7, 1960, Ser. No. 67,858
 5 Claims. (Cl. 68—18)

The present invention relates to clothes washing machines and more particularly to means for recirculating and filtering the water of a clothes washing machine.

Automatic clothes washing machines with which the present invention is associated comprise a cylindrical tub containing a cylindrical cup-shaped basket having an oscillatable agitator therein. The agitator is oscillated during the wash cycle of the machine and the basket is rotated at high speeds to extract the water from the clothes. Clothes are inserted into the basket and the basket is filled to the desired water level, after which the agitator is vigorously oscillated to provide the washing action. As the washing operation proceeds, lint and scum accumulate in the wash water and unless removed therefrom, will adhere to the clothes during the extraction cycle. Various systems have been employed for removing the lint and scum from the wash water, including overflowing the basket to wash the lint and scum down the drain. Other systems employ various methods of recirculation and filtering of the water in the basket of the machine. Most of these methods overflow water from the basket into the tub and pump the overflowed water back into the basket through some sort of filter. There are several disadvantages to such a recirculating system, however, in that some of the scum and filth that is present in the tub from the previous washing operation is circulated into the basket of fresh wash water when the washing cycle begins. Another undesirable feature of such a system is the cost requirement.

It is an object of the present invention to provide a filter system for a clothes washing machine which does not have the aforementioned undesirable characteristics of the prior recirculating systems.

The present system involves the use of the oscillating agitator to provide a recirculation of the fluid within the basket and a filter disposed on or about the top of the agitator in the path of the recirculated water to remove the lint and scum from the water.

The invention consists of the novel constructions, arrangements and devices to be hereinafter described and claimed for carrying out the above stated objects and such other objects as will appear from the following description of the preferred embodiment of the invention illustrated with reference to the accompanying drawings wherein:

FIG. 1 is a cross-sectional view of a washing machine having a new and improved agitator with a filter thereon;

FIG. 2 is a cross-sectional view of the agitator; and

FIG. 3 is a top view of the agitator partially broken away to show structural details of the agitator.

Referring to FIG. 1, there is disclosed a washing machine of the type disclosed in Gerhardt et al. Patent No. 2,807,951, October 1, 1957, and comprising a casing 10, an imperforate tub 11, and a vertically disposed imperforate wash basket 12. The basket 12 has disposed therein an agitator 13 which is oscillated by a conventional driving means. Water is supplied to the basket 12 by the water supply means 14 and access is provided to the basket 12 by means of a hinged door 15.

The agitator 13 comprises an upstanding hollow post portion 16 for receiving the usual oscillated drive shaft 17, a radially spaced wall 18 defining a water passageway 19 between the said wall and the post 16, and a down-

2

wardly and outwardly flaring base portion 21. Disposed about the outer surface and extending outwardly from the flaring base portion 21 are a plurality of vanes 22 for causing water turbulence within the basket 12 when the agitator is oscillated. A conical shaped, imperforate plate 24, having a plurality of spiral or helical vanes 23 disposed about the inner surface and extending outwardly to substantially the periphery of the flaring base 21, is suitably secured to the base of the agitator by means of a plurality of screws 25. The vanes 23 nest against the bottom surface of the agitator 13 thereby defining a plurality of helical shaped spaces 26 in the base of the agitator. A plurality of openings 27 in the agitator 13 provide fluid communication with the water passageway 19 and the spaces 26. A plurality of openings 28 are provided in the top of the flaring base 21 and are placed in the base so that they open into the spaces 26 at a point substantially forward of the end of the longest vane 23 thereby providing a pocket or cavity 26a in the agitator base.

An annular filter, designated generally by the reference numeral 29, is disposed on the agitator 13.

At the beginning of a washing operation, water is admitted to the basket 12 through the water supplying means 14 to fill the basket to the water level A shown in FIGURE 1, and the agitator 13 is oscillated by appropriate driving means.

The oscillation of the agitator in one direction fills the cavities 26a and oscillation in the other direction pumps the water upward through the helical-shaped spaces 26 and the water passes through the passageway 19, through the openings 27 and onto the filter 29. The water within the basket is thus continuously recirculated by means of the pumping action of the oscillated agitator.

Since any scum or lint in the water is of relatively light weight, it will be recirculated with the water as it flows through the agitator 13, and the filter member 29 arrests and removes the scum and lint from the circulating water.

This is a continuing application of an earlier filed United States patent application Serial No. 747,373, filed July 9, 1958, entitled Filtering Agitator which application has been permitted to lapse without prejudice in view of its being superseded by this application.

While we have described our invention in connection with a certain specific embodiment thereof, it is to be understood that this is by way of illustration and not by way of limitation and the scope of our invention is defined solely by the appended claims.

We claim:

1. In a clothes washing machine, a clothes receiving basket adapted to be filled with clothes and water to a predetermined level, an agitator disposed within said basket, means for oscillating said agitator, a filter disposed adjacent the top of said agitator and above said

predetermined level, means defining a water passage through said agitator and communicating with said filter and including a plurality of spaced spiral vanes within said agitator for pumping the water upwardly through said agitator.

2. In a clothes washing machine, a clothes receiving basket adapted to be filled with clothes and water to a predetermined level, an agitator disposed within said basket, means for oscillating said agitator, said agitator comprising a post portion for receiving a drive member and wall means radially spaced therefrom and defining a radial water passageway, said wall means terminating in a flaring base, a filter disposed on the top of the agitator above said level and in communication with said radial water passageway, means providing a plurality of spiral water passageways in said flaring base and in communication with said radial water passageway, means providing communication with said water in said basket with said

70

spiral passageways whereby when the agitator is oscillated, water in the basket will enter said last named means and be lifted upwardly by said spiral passageways through said radial passageways and will discharge onto said filter.

3. In a clothes washing machine, a clothes receiving basket adapted to be filled with clothes and water to a predetermined level, an agitator disposed within said basket, means for oscillating said agitator, said agitator comprising a post portion for receiving a drive member and wall means radially spaced therefrom and defining a radial water passageway, said wall means terminating in flaring base, a filter disposed on the top of the agitator above said level and in communication with said radial water passageway, a plurality of spaced spiral vanes providing a plurality of spiral water passageways in said flaring base and in communication with said radial water passageway, means defining at least one opening in the top of said flaring base above each of said spiral water passageways providing communication of said water in said basket with said spiral passageways whereby when the agitator is oscillated, water in the basket will enter said last named means and be lifted upwardly by said spiral passageways through said radial space and will discharge onto said filter.

4. In a clothes washing machine, a clothes receiving basket adapted to be filled with clothes and water to a predetermined level, an agitator disposed within said basket, means for oscillating said agitator, a filter dis-

posed adjacent the top of said agitator and above said predetermined level, means defining a water passage from below said predetermined level in communication with said filter, and a plurality of spaced spiral vanes within said passage connected to said agitator for pumping water upwardly through said passage from below said predetermined level to said filter.

5. In a clothes washing machine, a clothes receiving basket adapted to be filled with clothes and water to a predetermined level, an agitator within said basket and adapted to oscillate about a generally vertical axis, means for oscillating said agitator about said axis, a filter disposed adjacent the top of said agitator and above said predetermined level, means connected to said agitator and defining a water passage from below said predetermined level and in communication with said filter, and a plurality of spaced vanes within said passage angularly disposed with respect to said axis, said vanes being actuated by said agitator to pump water upwardly through said water passage from below said predetermined level to said filter.
